UNITED STATES PATENT OFFICE.

CHARLES EDGAR ANGELL, OF SALT LAKE CITY, UTAH, ASSIGNOR TO
IMOGENE ANGELL, ALEXANDER ROGERS, AND TRUMAN O. ANGELL,
JR., OF SAME PLACE.

SMOKER'S PIPE.

SPECIFICATION forming part of Letters Patent No. 651,689, dated June 12, 1900.

Application filed February 26, 1900. Serial No. 6,542. (No model.)

To all whom it may concern:

Be it known that I, CHARLES EDGAR ANGELL, a citizen of the United States, and a resident of Salt Lake City, in the county of 5 Salt Lake and State of Utah, have invented a new and Improved Tobacco-Pipe, of which the following is a full, clear, and exact description.

The purpose of this invention is to provide 10 a smoker's pipe which will evenly distribute the smoke in the mouth of the user, not concentrating it upon the point of the tongue, as in the ordinary form, and which will also prevent the entry of liquid charged with nicotine 15 into the smoker's mouth.

This specification is the disclosure of one form of the invention, while the claims define the actual scope thereof.

Reference is to be had to the accompanying 20 drawings, forming a part of this specification, in which similar characters of reference indicate corresponding parts in all the views.

Figure 1 is a sectional view of the invention. Fig. 2 is a section on the line 2 2 of 25 Fig. 1, and Fig. 3 is a section on the line 3 3 of Fig. 1.

The bowl *a* of the pipe is joined, as usual, to a stem formed in two parts *b* and *c*, the latter being preferably integral with the bowl 30 and the former having a nipple *b'*, removably fastened in the outer end of a chamber *c'* in the section *c* of the stem. The interior of the bowl *a* communicates with the chamber *c'* of the stem by way of preferably two small passages *a'*. By providing two passages they 35 may be made smaller in diameter than if one passage were employed, and the advantage of this is that the tobacco is caused to burn evenly in the pipe and prevented from being

40 drawn into the stem, at the same time in no way affecting the proper operation of the parts. The stem-section *c* has two small orifices *c'*, placing the chamber *c'* in communication with the atmosphere. By these means 45 a small quantity of atmospheric air is drawn into the stem of the pipe with the tobacco-smoke from the bowl, and this cools the

smoke when it is drawn into the mouth of the smoker. The stem-section *b* has an enlarged cavity in its upper end to receive the tubular valve-seat *d* of the mouthpiece *d*, which valve-seat serves also to fasten the mouthpiece to the stem. In the valve-seat *d* operates a ball-valve *e*, serving to admit the passage of the smoke to the mouthpiece, but preventing the breath from entering the smoke-passage, thereby avoiding the condensation of the moisture in the pipe-stem. The passage in the mouthpiece *d* instead of opening longitudinally of the mouthpiece is turned 55 upward at its discharge end and opens at the side of the mouthpiece, and this upturned end of the bore of the mouthpiece is covered by a distributor *d'*, in the form of a fan-shaped concavo-convex plate. This distributor deflects 60 the smoke and causes it to pass out from each side of the mouthpiece, thus avoiding the concentration of smoke directly against the point of the smoker's tongue, which disadvantage 65 is well known to exist in pipes previously constructed and results in injuring the tongue. The plate *d'* also prevents the saliva from entering the stem of the pipe.

It may be understood that with the construction here disclosed the saliva and condensed vapors resulting both from the moisture in the tobacco and from discharges at the mouth of the smoker will not be drawn back into the smoker's mouth laden with nicotine, as is usually the case. The pipe will 75 thus be kept clean and non-odorous, and the smoker will fully enjoy the tobacco without the usual inconveniences of smoking.

Having thus described my invention, I claim as new and desire to secure by Letters 85 Patent—

1. A mouthpiece for smokers' instruments, the passage of which is turned to discharge laterally from the mouthpiece, and a distributor-plate fastened rigidly to the mouthpiece and located over the discharge end of said passage, to deflect the smoke.

2. In a smoker's instrument, the combination of a stem, a mouthpiece, a tubular valve-

seat secured to one of said parts and fastened in the other, whereby to join said parts together, and a valve carried in the valve-seat.

3. A smoker's instrument, having a stem, 5 a mouthpiece separate therefrom, a valve-seat secured to one of said parts and entered into the other, to join the two together, and a valve in the valve-seat.

In testimony whereof I have signed my name to this specification in the presence of 10 two subscribing witnesses.

CHARLES EDGAR ANGELL.
